COMBING MACHINE

Joseph Fossel, Grafton, Mass., assignor to Alsatian Machine Works, Ltd., Boston, Mass., a corporation of Massachusetts

Application March 8, 1933, Serial No. 660,044

3 Claims. (Cl. 49—116)

The present invention relates to combing machines and particularly to a novel construction by which a positive feeding action of the sliver and also a positive detaching action is procured.

5 In prior devices of this character, the feed roller has been weighted and supported in engagement with a resilient cushion plate in an attempt to procure a positive feeding action of the sliver passing therebetween, as well as a positive holding action on the sliver during the operation of the detaching rollers. In these constructions, however, it has been impossible to obtain such a positive feeding and holding action as to provide for the formation of a uniform sliver as the latter passes beyond the detaching rollers. The inability of the feed roller to hold the sliver positively has resulted in weak spots in the sliver as it leaves the detaching rollers, and also results in an uneven drawing action when the sliver is later attenuated by drawing rollers in draw boxes or in drawing frames. Since the principal purpose of the combing action is to remove short fibers and to straighten and align the long fibers into a uniform sliver which will be uniform in weight throughout its width so that subsequent operations on the sliver will result in a uniform material free from weak or thin places, any failure of the comb to provide a uniform sliver will result in a non-uniform completed filament.

One of the principal objects of the present invention is to provide for feeding and holding of the sliver in the combing machine so that, during the advancing movement of the sliver, all portions of said sliver are advanced positively and uniformly, and so that during the detaching operation each individual fiber in the sliver will be positively held against unintended advancing movement with the exception of the few end fibers intended to be detached, so that a uniform detaching operation is procured.

In order to provide a uniform sliver, it is necessary to obtain, in addition to the uniform feeding and holding action, a positive detaching action, and a further object of the invention is, accordingly, to provide for a positive detaching by a mechanism by which the combed fibers projecting beyond the end of the cushion plate and not securely held by the feed roller will all be positively detached from the sliver. This positive detaching action, in connection with the positive feeding action, results in a completed sliver which is of a uniform weight throughout.

According to the present invention, the feed roller and the detaching roller are formed so

that a positive clamping action is obtained by said rollers on the sliver, thereby providing for a positive control and movement of each individual fiber in the sliver during the operation of the comb. To this end, the rollers are provided with a relatively small number of teeth or ribs presenting outer surfaces of substantial width with the spacing between said ribs sufficiently great to prevent a positive clamping of the fibers at any points except between the outer ends of the flutes and the cooperating pressure member.

Other and further objects and advantages of the invention will appear from the following detailed description taken in connection with the accompanying drawing, in which:

Fig. 1 is a vertical section through the feeding mechanism and the detaching rollers of a combing machine, this view being substantially along the line 1—1 of Fig. 2.

Fig. 2 is a front elevation of the nipper blade, the feed roller, and the cushion plate, the detaching rollers having been removed.

Fig. 3 is an end elevation of the feeding mechanism.

Fig. 4 is an enlarged fragmentary vertical section showing the cooperation of the feed roller and cushion plate.

Fig. 5 is an enlarged fragmentary sectional view of one of the detaching rollers.

Like reference characters refer to like parts in the different figures.

Referring first to Fig. 1, the sliver 1 passes between a feed roller 2 and a cushion plate 3 and is advanced by said roller over the forward end of the cushion plate between a nipper blade 4 and the forward end 5 of said cushion plate. The cushion plate, feed roller and the nipper blade are all mounted on the nipper frame 6 which, during the operation of the comb is advanced toward the detaching rollers 7 and 8 for a detaching operation and retracted from said detaching rollers for a combing operation on the part of the fibers projecting beyond the nipper blade 4. The mechanism by which this is procured is not shown and may be of any suitable well-known construction, as disclosed for example in the patent to Tunstall No. 1,351,076, granted August 31, 1920. The nipper blade 4 is carried on arms 10 and 11 journaled on a shaft 12 for movement of said blade toward or away from the end 5 of the cushion plate. The combing cylinder and the operating mechanism for the nipper blade have not been indicated in the drawing, since the operation of this structure in connection with the re-

mainder of the mechanism is well known and fully described in the above cited Tunstall patent.

The back detaching roller 7 is mounted in fixed bearings in the comber frame and cooperates with an oscillatory pressure roller 13, which is positioned above the roller 7 and is carried by an arm 14, the latter being movable in the usual manner by any suitable mechanism to oscillate said roller 13 over the surface of the detaching roller for procuring the detaching operation. The front detaching roller 8 cooperates with a pressure roller 15 mounted in fixed bearings not shown to carry the sliver away from the detaching roller 7.

The above described structure is, in general, well known in combing machines and is not, of itself, the invention of the present application. The latter involves the particular formation of the feed roller, the cushion plate and the detaching rollers so that, as above stated, a positive feeding and detaching operation is procured.

Referring now to Fig. 1, the cushion plate 3 has a horizontal portion of a material depth with a vertical integral portion 16 projecting upwardly in back of the feed roller and forming with the horizontal portion a rigid cushion plate which will not be distorted during the operation of the feed roller. The surface 17 of the cushion plate over which the sliver is moved by the feed roller has a portion 18 directly beneath the feed roller 2 which is slightly greater in radius than the radius of the feed roller, and which is arranged to provide for contact between said surface and at least three of the teeth on the feed roller at all times. The point of contact between the cushion plate and the feed roller is directly beneath the center of said roller, as will be apparent from Fig. 4, and from this point, the surface 17 gradually retracts from the surface of the feed roller on a larger radius to form a smooth curve over which the sliver is advanced. Forwardly of the surface 18 of the cushion plate is located the end 5 of the cushion plate, which end engages, as above stated, with the nipper blade 4 during the combing operation.

The feed roller 2 is provided with a relatively small number of ribs 20 on the periphery thereof, each rib providing an outer flat surface 21 of material width for engagement with the surface 18 of the cushion plate. Each of the surfaces 21 is concentric to the axis of the roller and is substantially one-sixty fourth of an inch in width and the opposite sides of each rib extend at an angle of substantially forty-five degrees to each other. The diameter of the roller 2 is sufficiently great to avoid any bending of said roller during the movement of the sliver between said roller and the cushion plate, and in the construction shown is substantially one and one-eighth inches in diameter. It has been found that for proper operation of the feeding mechanism a roller having twenty-four ribs for a diameter of one and one-eighth inches is preferable in order to obtain positive feeding of the sliver without crushing of the fibers.

The feed roller 2 is urged into engagement with the cushion plate 3 at a predetermined pressure. Referring now to Figs. 2 and 3, the ends of the roller 2 provide bearing surfaces 22 which are engaged by bearing blocks 23. Each of the bearing blocks is carried on a vertical rod 24 slidable in openings provided by horizontally projecting ears 25 on the nipper frame 6. A spring 26 surrounds each rod 24 and engages at one end, one of

the ears 25; the other end of the spring engages a collar 27 secured against movement on the rod 24. The springs 26 located at opposite ends of the feed roller maintain a positive predetermined pressure vertically downward on said roller, which maintain the ribs of the roller in positive engagement with the arcuate surface 18 of the cushion plate.

The width of the arcuate surface 18 as above stated is sufficient to provide for engagement of at least three of the ribs of the feed roller therewith at all times, and the positive action of the springs 26 thereby maintains a plurality of distinct clamping actions between each of said ribs and the cushion plate, so that each individual fiber in the sliver is securely held against unintended movement during the action of the detaching rollers. During the rotation of the feed roller 2 to procure advancing movement of the sliver, the definite engagement between the cushion plate and the plurality of ribs with the feed roller results in a positive feeding action, thereby providing for a definite advance of each fiber of the sliver to the desired extent.

In order to procure a uniform sliver following the action of the detaching rollers, it is necessary to provide for a positive detaching action. To this end, the detaching rollers 7 and 8 are each provided with a series of ribs corresponding in shape to the ribs on the feed roller 2. As shown in Fig. 5, the roller 7 which is substantially one inch in diameter in the particular arrangement shown is preferably provided with approximately thirty-three ribs 28, this particular number of flutes being found to operate most satisfactorily in the positive detaching of the fibers from the sliver. Each of the ribs 28 has an outer surface 30 substantially one-sixty fourth of an inch in width, and the opposite faces 31 of each of the ribs extend at an angle of substantially forty-five degrees to each other. The width of the outer surfaces on successive ribs varies slightly from the basic width on the order of from two to seven-thousandths of an inch to avoid the formation of permanent grooves in the smooth surface of the cooperating pressure roller 13.

The operation of the combing machine in general corresponds to the operation of the comber disclosed in the above cited Tunstall patent. It will be noted that as the nipper frame 6 advances into the position indicated in Fig. 1, the nipper blade 4 is elevated out of engagement with the tip 5 in a cushion plate, and the feed roller 2 is turned clockwise to procure a predetermined advance of the sliver 1. As the nipper frame reaches the advanced position shown, the counterclockwise rotation of the detaching roller 7, which occurs at this time engages, the end of the fibers of the sliver which have been previously combed, and draws them out of the remainder of the sliver held by the feed roller 2. The particular construction of the feed roller 2 in connection with a rigidly formed cushion plate, which latter by reason of its integral upwardly extending portion 16 retains its proper configuration regardless of the thickness of the sliver passing between said plate and the roller 2, provides as pointed out above, for a positive advance of the sliver during the turning movement of said roller and also for a positive holding of the fibers of the sliver during the detaching action of the roller 7 cooperating with the pressure roller 13. The detaching roller 7, as will be apparent, obtains by the configuration of the ribs thereon a positive clamping action between said ribs and the

cooperating pressure roller, and thereby procures a positive separation of the end fibers in the sliver from the mass of fibers held by the feed roller.

It may be noted that the novel type of fluting 5 on the feed roller is such that the sliver maintains a uniform width as it passes between said roller and the cushion plate. It has been possible by the present invention to eliminate the heretofore necessary guides on or adjacent the 10 cushion plate which prevented the sliver from spreading between the feed roller and the detaching roller. The elimination of the guides results in a more uniform detaching action, as will be apparent, and also eliminates excessive "fly" 15 which is necessarily an incident to a combor which requires guides for holding the sliver to the desired width.

From the foregoing, it will be apparent that the invention resides particularly in the provision 20 of a feed roller having ribs arranged in such a manner as to provide for positive engagement between said roller and the cushion plate, which latter is also arranged to provide a rigid surface against which the sliver is clamped by said feed 25 roller. The arcuate surface of the cushion plate is arranged to provide for a positive engagement between at least three of the ribs on the feed roller and said surface at all times. In conjunction with the novel feed roller and cushion 30 plate, the invention involves the provision of a detaching roller having a novel arrangement of fluting on its periphery to provide for a positive detaching action. The novel detaching roller cooperates with the feed roller and cushion plate 35 to produce a more uniform resulting sliver than has been previously obtained in prior art mechanisms.

I claim,

1. In a combing machine, the combination of 40 a feed roller having a relatively small number of ribs, each of which presents an outer surface of material width, with the opposite faces of each rib extending at an angle of substantial forty-five degrees to each other, said outer surfaces 45 being all substantially one sixty-fourth of an inch in width, and a cushion plate providing a rigid arcuate surface of sufficient width for en-

gagement simultaneously with at least three of the ribs on the roller, said roller being supported in a position for engagement with said surface, and means for urging said roller towards said plate with a predetermined pressure.

2. In a combing machine, the combination with 5 a cushion plate providing a smooth rigid surface, of a feed roller engaging said plate, said roller having a relatively small number of ribs, each presenting an outer surface of material width, 10 with the opposite faces of each rib extending at an angle of substantially forty-five degrees to each other, said outer surfaces being all approximately one sixty-fourth of an inch in width, and a detaching roller cooperating with said feed 15 roller and cushion plate, said detaching roller having a relatively small number of ribs each presenting an outer surface of substantial width 20 with the opposite faces of each of said ribs extending at an angle of substantially forty-five degrees to each other, said outer surfaces of the detaching roller being all substantially uniform in width.

3. In a combing machine, the combination of 25 a detaching roller having a relatively small number of ribs in the periphery thereof, the outer surface of each of said ribs being of material width and concentric to the axis of the roller with the opposite faces of each rib extending at an angle of substantially forty-five degrees to each other, 30 said outer surfaces being all approximately one sixty-fourth of an inch in width, and means for positively holding the sliver in the machine during the operation of said detaching roller, said means comprising a rigid cushion plate presenting 35 a smooth arcuate surface cooperating with a feed roller, the latter having a relatively small number of ribs with the opposite faces of each of said ribs extending at an angle of substantially forty-five degrees to each other, said ribs each 40 having an outer surface of substantial width, the said outer surfaces being all approximately one sixty-fourth of an inch in width, with the arcuate surface of said plate of sufficient width for engagement simultaneously with at least 45 three of the ribs on the roller.

JOSEPH FOSSEL.
